UNITED STATES PATENT OFFICE.

GEORGE ALBERT HOFFMAN, OF MANSFIELD, OHIO.

GAS HEATER.

1,410,807.

Specification of Letters Patent. Patented Mar. 28, 1922.

Application filed August 8, 1921. Serial No. 490,629.

To all whom it may concern:

Be it known that I, GEORGE A. HOFFMAN, a citizen of the United States, residing at Mansfield, in the county of Richland and State of Ohio, have invented certain new and useful Improvements in Gas Heaters; and I do declare the following to be a full, clear, and exact description of the invention, such as will enable others skilled in the art 10 to which it appertains to make and use the same.

My invention relates to improvements in gas heaters of the type in which a plurality of hollow heat radiating members or "radiants" are mounted against a fire-back, and the object of the invention is to provide novel means whereby a part of the holding means for the heat radiating members, acts also as part of the means which holds the 20 fire-back in the heater casing.

With the foregoing in view, the invention resides in the novel subject matter herein-after described and claimed and shown in the accompanying drawing.

25 Figure 1 is a front elevation partly in section, showing a portion of a gas heater constructed in accordance with my invention.

Figure 2 is an end elevation with parts broken away and shown in section.

30 Figure 3 is a detail vertical sectional view through the upper end portion of the fire back.

Figure 4 is a detail end view of one of the "radiants."

35 In the drawing above briefly referred to, the numeral 1 designates an appropriate casing having the usual end walls, 2. Within the lower portion of the casing, a suitable burner 3 is mounted and over this burner, a horizontal supporting plate 4 extends across 40 the interior of the casing, said plate being longitudinally depressed to form a channel 5 and being pressed upwardly in advance of said channel to provide a longitudinal rib 6.

45 The portion of the plate 4 between the channel 5 and the rib 6 is provided with a plurality of openings 7 located above the several jets of the burner 3.

The numeral 8 designates an upstanding 50 fire back formed of any appropriate material, the front side of said fire back being formed with a shallow recess 9 which is approximately co-extensive therewith, comparatively narrow vertical walls 10, how-

ever, being left at the vertical edges of the fire back while a wider wall 11 extends across the upper edge portion thereof. The lower edge of the main body portion of the fire back 8 is received removably in the channel 5 and the ends of this channel are preferably turned forwardly as indicated at 5^a in Fig. 2, whereby to receive the lower ends of the walls 10. The upper end portion of the fire back 8 is secured in place within the casing 1 by novel means yet to be described. 65

Filling the recess 9 and disposed side by side, are a number of vertical "radiants" or radiating members which are of hollow formation and formed of such material as to be heated to incandescency by the jets from the 70 burner 3. The lower ends of the "radiants" 12 rest on the plate 4 between the rib 6 and the body portion of the fire back 8 while the upper end of said "radiants" are provided with upstanding lugs 13 which are received 75 in a longitudinal channel 14 with which the lower edge of the wall 11 is formed. As shown, the lugs 13 terminate in spaced relation with the upper side of the channel 14 so as to permit upward movement of the 80 "radiants" 12, this upward movement being necessary in order to free the lower end of any "radiator" from the rib 6 when it is to be removed, for instance to be replaced by a new part. The construction in question also 85 facilitates assembly of the device as will be readily understood.

As shown most clearly in Fig. 1, the ends of the channel 14 continue through the vertical walls 10 and open at opposite vertical 90 edges of the fire back 8, these channel ends receiving nuts 15 formed of any appropriate heat-resisting material. In the practical manufacture of the device it is desirable to have the ends of the channel 14 extend to 95 the vertical edges of the fire back and screws 16 are passed through the end walls 2 and threaded into said nuts as indicated most clearly in Figure 1.

From the foregoing, taken in connection 100 with the accompanying drawing, it will be seen that I have provided an extremely simple and inexpensive, yet a highly efficient and desirable arrangement of parts for mounting the fire back in the casing and for 105 detachably securing the "radiants" in place. Since excellent results are obtainable from the details disclosed, they are by preference

followed, but it is to be understood that within the scope of the invention as claimed, numerous minor changes may be made.

I claim:

- 5 1. A gas heater comprising a casing, a fire-back in said casing whose front side is formed with a recess approximately co-extensive therewith and adapted to contain vertical heat-radiating members, the upper wall 10 of said recess having a downwardly opening longitudinal channel whose ends extend through both vertical edges of the fire-back, said channel being adapted to receive the upper ends of the heat-radiating members, 15 nuts contacting with the inner side of the casing at the ends of said channel, and screws passing inwardly through the casing and threaded into said nuts, said screws being within the ends of said channel to retain the fire-back in the casing.
2. A gas heater comprising a casing, a fire-back in said casing whose front side is formed with a recess approximately co-extensive therewith and adapted to contain vertical heat-radiating members, the upper wall 25 of said recess having a downwardly opening longitudinal channel whose ends extend through both vertical edges of the fire-back, said channel being adapted to receive the upper ends of the heat-radiating members, 30 heat-resisting casing-protecting plugs filling the ends of the channel, and screws passing through the walls of the casing and having their inner ends threaded into the outer ends of said plugs, whereby to secure the plugs in 35 said channel and to hold the fire-back in said casing.

In testimony whereof I have hereunto set my hand.

GEORGE ALBERT HOFFMAN.
